UNITED STATES PATENT OFFICE.

JOHN A. RATHBONE, OF UTICA, NEW YORK.

METHOD OF FORMING SAND MOLDS.

No. 836,342.

Specification of Letters Patent

Patented Nov. 20, 1906.

Application filed March 5, 1906. Serial No. 304,387.

To all whom it may concern:

Be it known that I, JOHN A. RATHBONE, a citizen of the United States of America, residing at Utica, in the county of Oneida and State of New York, have invented certain new and useful Improvements in Methods of Forming Sand Molds, of which the following is a specification, reference being had therein to the accompanying drawings.

10 In the present state of the art it is almost universal practice in the formation of sand molds to fill the loose sand into the flask upon an up-facing pattern and then to compact the sand either by tamping or by pressure. 15 The advantage of this method is that the interstices of the pattern are filled with sand by gravity, while the impact of the sand against the pattern face causes a certain degree of compression. As a consequence a perfect 20 imprint of the pattern is thus initially formed and the subsequent tamping or pressure will impart the proper degree of hardness to all portions of the molding-face.

25 In multiple molding, where it is necessary to form molding-faces upon opposite sides of the flask, the lower face only can be formed by this method. It has therefore been found impracticable to form a good imprint of the pattern upon the upper face of the sand and 30 for the reason that the movement of the pattern downward into the sand will cause the projecting portions to carry the sand away from the face of the depressions or interstices of the pattern, leaving soft spots in the molding-face, which will not retain the proper 35 shape. Thus gravity, which assists in the formation of the molding-face against the up-turned pattern, has precisely the opposite effect in the formation of the face by the down-turned pattern.

40 With the present invention difficulty of forming an imprint of the down turned pattern is overcome by increasing the velocity of movement of the said pattern relative to the body of loose sand to such an extent as to practically eliminate gravity as a factor and to compact the sand against the pattern-face by inertia. This may be accomplished either by moving the sand-holder upward in 45 relation to a stationary pattern or by moving the pattern downward in relation to a stationary sand-holder; but in either case the

essential factor is the requisite velocity of the moving part.

In carrying out my improved method I 55 preferably employ a molding-machine such as illustrated in the drawings, in which—

Figure 1 is a vertical section through the mold-flask and opposed patterns before the operation of compacting the sand. Fig. 2 is 60 a similar view after the compacting operation. Fig. 3 is a section through a portion of the mold, illustrating in dotted lines the defect overcome by the invention.

A is a mold-flask, B an upturned pattern, 65 and C the opposed or downturned pattern. These patterns are mounted upon relatively movable members of a molding-machine of any suitable construction which is capable of imparting the required velocity to the movable member. As shown, the pattern B is secured to lower head D, upon which the flask A is also carried, and this head is secured to a plunger E, moved upward by any suitable means. (Not shown.) The down-face pattern C is secured to a stationary upper head F.

G is a sand-frame or other suitable means for retaining the proper quantity of loose sand to fill the mold-flask when compacted 80 between the opposed pattern-faces.

In operation, the flask A being placed upon the head D, loose sand is filled therein and into the sand-frame G thereabove and is struck off flush with the top of the latter. 85 Motion is then imparted to the plunger E, which carries upward the head D, pattern B, flask A, and sand-frame G, and by the time the upper pattern C contacts with the sand the parts are moving at a high velocity. Inertia will thus cause the sand to enter all the interstices of the downturned pattern and to strike against the face thereof with sufficient impact to form a perfect imprint. This formation of the molding-face occurs in advance of the completion of movement of the head D, so that during the final movement the body of sand between the molding-faces may be compressed the requisite degree of 95 hardness. In place of moving the body of sand upward in relation to the down-facing pattern the pattern may be moved downward in relation to the and the same 100 effect produced.

What I claim as my invention is—

1. The method of forming sand molds which consists in relatively moving toward each other a body of sand and a down-facing superposed pattern, with sufficient velocity to compact the sand against the pattern-face by inertia.
2. The method of forming sand molds which consists in filling a holder with loose sand, superposing a down-facing pattern in relation thereto and imparting a relative movement of sufficient velocity to compact the sand against the pattern-face by inertia.
3. The method of forming sand molds which consists in filling a mold-flask with sand upon an up-facing pattern, superposing a down-facing pattern in relation thereto and relatively moving said patterns with sufficient velocity to compact the sand against the up-
per pattern-face by inertia.
4. The method of forming sand molds which consists in relatively moving a body of sand and an opposed pattern-face, with suffi-

cient velocity to compact the sand against said face by its inertia and whereby gravity 25 is a negligible factor in the operation.

5. The method of forming sand molds which consists in imprinting a pattern in a body of sand by relatively moving said pattern and body of sand with a sufficient velocity to compact the sand against the face of the pattern by the inertia of the sand, unassisted by gravity.

6. The method of forming sand molds which consists in imprinting a pattern in a 35 body of sand by relatively moving said pattern and body of sand with sufficient velocity to compact the sand against the pattern-face by the inertia of the sand, acting contrary to gravity.

In testimony whereof I affix my signature in presence of two witnesses.

JOHN A. RATHBONE.
